(57) **CLAIM**

The ornamental design for a shoe sole, as shown and described.

DESCRIPTION

FIG. 1 is a top-front perspective view of the shoe sole; FIG. 2 is a front view of the shoe sole of FIG. 1; FIG. 3 is a back view of the shoe sole of FIG. 1; FIG. 4 is a left side view of the shoe sole of FIG. 1; FIG. 5 is a right side view of the shoe sole of FIG. 1; FIG. 6 is a top view of the shoe sole of FIG. 1; and, FIG. 7 is a bottom view of the shoe sole of FIG. 1. The broken lines in the drawings illustrate environmental structure in the form of a shoe upper and form no part of the claimed design.

1 Claim, 7 Drawing Sheets
